SHEET METAL RECEPTACLE

William Howard Nesbitt, Wheeling, W. Va., assignor to Wheeling Corrugating Company, Wheeling, W. Va., a Corporation of West Virginia

Application January 17, 1930. Serial No. 421,431

2 Claims. (Cl. 220—69)

This invention relates broadly to sheet metal receptacles, and more specifically to a bottom structure for such receptacles.

The chief object of the invention is to provide a receptacle, designed primarily for use as a container for garbage or other refuse, having its interior devoid of abrupt angles in which dirt and refuse material may collect, and which, consequently, may be conveniently and thoroughly cleansed for rendering its condition comparatively sanitary.

A further object is to provide a receptacle comprising a substantially cylindrical body and an attached bottom, the latter being of shallow bowl shape and having interiorly a concave, or rounded, curvature intermediate its substantially horizontal and upright surfaces, whereby the cleansing of the bottom is facilitated.

In describing the invention in detail, reference is herein had to the accompanying drawing, in which—

Figure 1 is a view of a garbage can partly in side elevation and partly in vertical section, showing my invention; and—

Figure 2 is an enlarged fragmentary section of the same.

Referring to said drawing, 1 designates the substantially cylindrical body portion of a sheet metal receptacle, said body being more or less of a conventional form employed in garbage cans and pails. Attached to the lower end of said body through the intermediacy of an annularly disposed double seam 2 is the upper end of the substantially upright wall portion 3 of a one-piece sheet metal bottom, designated generally by the reference numeral 4. Said bottom, formed by a metal-pressing or drawing method well understood in the art, is of shallow bowl shape, having a substantially flat base portion 5 and the aforesaid upright wall portion 3, the latter possessing substantial height, as shown. Intermediate said wall portion 3 and said substantially flat, or horizontal, portion 5, said bottom 4 presents interiorly a concavely curved or rounded portion 6, without joint or seam, every part of the surface of which is readily accessible for thorough cleansing.

A foot or base whereon the structure may rest is constituted by a sheet metal ring or band 7 which embraces the upright wall portion 3 of the bottom 4 and which preferably has its upper edge located in more or less closely underlying relation to the externally-disposed double seam 2. Said band is pressed upward into closely embracing relation to said bottom and is rigidly secured to the latter, preferably by spot-welding, as indicated

at 8. Said band has therein an inwardly pressed bead which occupies partially underlying relation to the curved portion 6 of the receptacle bottom 4, as shown.

The lower portion of said band, or that portion 60 located below said bead has a skirt-like form extending downwardly below the level of the horizontal portion 5 of the bottom 4 to form a foot-like portion upon which the receptacle may rest. The lower edge, or foot portion, of said 65 band may have the plain form shown or may be made of any other preferred form.

From the foregoing it will be understood that the structure embodies no bottom joint or abrupt angle in which particles of refuse material 70 may find lodgement and that, therefore, the smooth interior of the receptacle may readily be cleansed and kept in a sanitary condition.

What is claimed is—

1. A sheet metal receptacle comprising a substantially cylindrical body and a one-piece bottom, said bottom including a base portion and an upright cylindrical wall portion joined by an arcuately curved portion, said wall portion being permanently seamed to said body, and a sheet 75 metal band attached to and occupying annularly embracing relation to said bottom, said band having its upper edge in underlying seated relation to said seam and being provided intermediate its upper and lower edges with an inwardly 80 directed annular bead, arcuate in cross section disposed in conformably seated underlying relation to said curved portion of the bottom.

2. A sheet metal receptacle comprising a substantially cylindrical body and a bowl-shaped 90 bottom, said bottom having a substantially horizontal base portion, a substantially upright cylindrical wall portion and a convexly curved or rounded portion intermediate said base and wall 95 portions, said curved portion affording a continuously smooth interior surface, the upper end of said wall portion being seamed to said body, and a base comprising a sheet metal band attached in annularly embracing conformably seated relation to the upright wall and a substantial part of said curved portion of said bottom and having its upper edge disposed in underlying seated relation to the bottom-attaching seam, said band having its lower edge portion 100 depending below the level of the base portion of said bottom, said lower edge portion having outwardly flared skirt form and constituting supporting means for the base portion.
